United States Patent Office

Des. 185,307
Patented May 26, 1959

185,307

MOTOR COACH

Maurice E. Moore, Dallas, Tex.

Application March 3, 1958, Serial No. 49,865

Term of patent 14 years

(Cl. D14—3)

Fig. 1

Fig. 4

Fig. 2

Fig. 3

Figure 1 is a side elevation of the motor coach;
Figure 2 is a front end elevation of the motor coach;
Figure 3 is a rear end elevation; and
Figure 4 is a side elevation of the side opposite Figure
1, all showing my new design.

I claim:

The ornamental design for a motor coach, substantially as shown.
